UNITED STATES PATENT OFFICE.

JOSEPH H. LITTLE, OF NEW YORK, N. Y.

WASTE-PIPE PLUG.

SPECIFICATION forming part of Letters Patent No. 629,196, dated July 18, 1899.

Application filed February 24, 1899. Serial No. 706,677. (No model.)

To all whom it may concern:

Be it known that I, JOSEPH H. LITTLE, a subject of the Queen of Great Britain, residing in the city of New York, borough of Manhattan, in the county of New York and State of New York, have invented a new and Improved Waste-Pipe Plug, of which the following is a full, clear, and exact description.

This invention relates to improvements in plugs for waste or discharge pipes of washbasins, washtubs, or sinks and the like. With the ordinary form of plug a chain is used for securing it to a basin or tub or the like. Such chains are not only unsightly and sometimes 15 obstructions, but they are always more or less dirty, the links being covered inside with verdigris and impossible to clean. Further, a chain carries the dirt from one wash to the clean water of the next wash, and this obviously is a serious objection, especially in public places.

The object of my invention is to obviate the before-mentioned objections by providing a chainless plug of simple and comparatively 25 inexpensive construction and having means by which it may be readily and quickly attached to any basin or tub, whether old or new.

I will describe a waste-pipe plug embodying my invention and then point out the novel 30 features in the appended claims.

Reference is to be had to the accompanying drawings, forming a part of this specification, in which similar characters of reference indicate corresponding parts in both the figures.

Figure 1 is a section of a washbasin with a plug embodying my invention as applied thereto, and Fig. 2 is a top view of the plug.

Referring to the drawings, 1 designates a plug of any suitable material—such, for instance, as a flexible material or metals. The plug has a finger-piece 2, and I have here shown it as provided with a packing-ring 3 of soft material—such, for instance, as rubber—so as to make a water-tight connection between it and the discharge-pipe 4. At one end of and having swinging connection with the plug 1 is a keeper-link 5, designed to engage around one of the members of the strainer 6, arranged in the waste or discharge pipe. This link 5 has its upper portion extended loosely through a lug formed on the lower end of the plug 1, and its opposite sides are convergent

until they meet at a point below the strainer, as indicated at 7. Below this point 7 the members of the link 5 are divergent and then 55 extended inward and then upward to form hook portions 8.

In operation in applying the plug to a new or old basin or the like the link will be forced downward over a member of the strainer 6. 60 In this operation the hook portions 8 will be spread apart, so as to readily pass the member of the strainer, as will also the members at the point 7. When water is to be retained in a basin or the like, a plug will be inserted, 65 as indicated in Fig. 1. When it is desired to draw the water, however, the plug will be drawn upward until the portion 7 of the link comes above the member of the strainer, as indicated in dotted lines in Fig. 1, and when 70 in this position the plug will be retained open; but the hook portions 8 will prevent the plug from being wholly detached by engaging with the under side of the strainer member, but when, however, it is desired to wholly remove 75 the plug the members of the link 5 may be spread outward by any suitable means to allow the strainer member to pass between the hooks.

While I have indicated the link 5 as having 80 swinging connection with the plug, it is obvious that there may be a rigid connection between the two parts.

Having thus fully described my invention, I claim as new and desire to secure by Letters 85 Patent—

1. The combination with a waste-pipe plug, of a link attached thereto and comprising two members convergent to a meeting-point in a portion of their length and then divergent and 90 having inwardly-turned hook ends, substantially as specified.

2. The combination with a waste-pipe plug, of a link having swinging connection with the plug, the said link consisting of resilient metal 95 having two members convergent to a meeting-point in a portion of their length and then divergent from said meeting-point and having inwardly-turned hook ends, substantially as specified.

JOSEPH H. LITTLE.
